UNITED STATES PATENT OFFICE.

JOHN H. WETTENGEL, JR., OF ROCHESTER, NEW YORK.

CHAIR-SEAT.

1,147,287.

Specification of Letters Patent. Patented July 20, 1915.

Application filed December 16, 1913. Serial No. 807,148.

To all whom it may concern:

Be it known that I, JOHN H. WETTENGEL, Jr., a citizen of the United States, residing at Rochester, in the county of Monroe and State of New York, have invented new and useful Improvements in Chair- Seats, of which the following is a specification.

The invention relates to chairs, and more particularly to seats therefor, and has for an object to provide a seat for chairs or other articles of furniture and which can be cheaply manufactured and readily and quickly applied to the furniture.

The invention contemplates, among other features, the provision of a seat for chairs or other furniture and which seat can be either round, rectangular, elliptical or any other desired shape, the seat being so arranged and consisting of parts which can be readily attached together and applied to the chair to form a strong and substantial seat which will present a neat and effective appearance.

In the further disclosure of the invention reference is to be had to the accompanying drawings, constituting a part of this specification, in which similar characters of reference denote corresponding parts in all the views, and in which:

Figure 1 is a fragmentary perspective view of a chair showing my seat applied thereto; Fig. 2 is a perspective view of the rim; Fig. 3 is a vertical sectional view showing the manner of applying the seat body to the rim; and Fig. 4 is a vertical sectional view showing the rim after the same has been bent to secure the seat body thereto.

Referring more particularly to the views, I disclose a rim 10 and which in this instance is of a circular nature and is preferably made of stamped metal, the said rim being so formed and constructed as to provide a depression 11 bounded by side walls 12 and 13, the first of which I will term the inner side wall and the latter the outer side wall. The inner and outer side walls 12 and 13 are provided with vertical cuts 14 so that the material from which the rim 10 is formed will permit of readily bending the side walls 12 and 13, as will be hereinafter more fully disclosed.

A seat body 15 of cane or the like is adapted to be placed upon the rim 10 and the edge 16 of the seat body 15 is pressed into the

depression 11, it being understood that the seat body has been preferably cut to a size corresponding to the size of the rim 10 so that when the seat body is placed upon the rim its edge will be in a position to be pressed into the depression as mentioned. When this has been accomplished the outer side wall 13 is pressed tight against the edge of the rim reposing in the depression and the inner and outer side walls with the edge of the rim therebetween are then bent downwardly and inwardly to lie against a flange 17 forming a part of the rim 10, as shown in Fig. 4.

The rim 10, having the seat body 15 rigidly attached thereto as mentioned, is now placed upon a chair 18 and when properly positioned thereon suitable upholstering nails 19 are hammered or otherwise forced through the flange 17, the inner and outer side walls 12 and 13 and the edge 16 of the seat body 15, thus rigidly securing the rim and seat body to the chair and also aiding in further securing the seat body to the rim. When the said body has been applied to the rim and the edge or inner and outer side walls of the rim have been bent upon the body of the rim as mentioned, it will be apparent that any slack in the seat body will be taken up by the bending operation so that the seat body will be tight and free from creases or wrinkles.

From the foregoing description it will be apparent that the device described is of a simple character, consists of few parts and can be cheaply manufactured.

Having thus described my invention, I claim:

A chair seat comprising a seat body mounted on an integral circular frame consisting of a plurality of thicknesses bent one upon the other, the seat body extending over the upper surface of the frame and having its edge bent downwardly and inwardly and secured between adjacent thicknesses of the frame, the upper surface and edge of the seat being thus free from any metallic parts projecting beyond the seat body.

In testimony whereof I affix my signature in presence of two witnesses.

JOHN H. WETTENGEL, Jr.

Witnesses:

JOHN WETTENGEL,

WALTER E. YOUNG.
